UNITED STATES PATENT OFFICE

2,099,861

PAD FILLING APPARATUS

Thomas L. McJoynt, Janesville, Wis.

Application February 5, 1934, Serial No. 709,685
Renewed April 11, 1936

11 Claims. (Cl. 226—43)

My invention relates generally to improved means for filling upholstery pads or the like, the principle of which is similar to that employed in the device for filling pads described in my Patent Number 1,828,673 of October 20, 1931.

The above named patent shows and describes a machine for blowing filling material into a pad. It discloses mechanism for alternately filling individual sections of pads located adjacent each other. The filling material is blasted through diverging nozzles and is alternately diverted from one nozzle to the other through the medium of a deflector so that only one nozzle is in operation at a time.

My improved device is so constructed and arranged as to permit all of the sections in a single pad to be filled simultaneously. However, in the improved machine I have retained the diverging nozzle structure common in my original device which permits of continuous filling of pads by diverting the flow of material from one set of nozzles to the other.

On first thought, the problem of simultaneously filling the separated sections of a pad seems to be a simple one. However, the fact that cotton fiber forms the basis of the filling material used makes it an involved one. As is explained in my patent heretofore named, the filling material is blasted into a section of a pad through a nozzle sleeve, the nozzle and pad being relatively withdrawn one from the other as the filling proceeds, by the force of air pressure from the nozzle. The speed of the withdrawal of the nozzle or the withdrawal of the pad away from the nozzle is therefore determined by the speed with which the filling material builds up within the pad section ahead of the said nozzle.

Due to the consistency of the filling material and the method of breaking it up, it does not flow from the nozzle in a continuous stream. For that reason there is no determined speed with which the nozzle is withdrawn from the sections of a pad. It may be necessary to slow down the withdrawal of the nozzle at one point and speed it up at another in order that the connected pad section may be uniformly filled.

To apply this principle and utilize the same mechanism that I use in the device shown in my patent to a number of nozzles all being withdrawn from the multiple sections in a single pad at the same time would be fatal to the effective operation of the device for the reason that one nozzle might deliver more or less filling material than another and, therefore, one or more sections of the pad would fill up faster than another,

in which event the section that did not receive as much filling material as the other would appear flabby and soft as compared to those that had the proper amount of filling material.

If the rearward movement of the nozzle sleeve were slowed up as to permit the section getting the lesser amount of filling material to pack properly, the stream of cotton from the other nozzles would pack against the exhaust ends of the telescoped nozzles, which action would prevent air from escaping through the fabric of the pad, the said nozzle would clog and it would be necessary to pull it clear of the pad and blow it free before the filling operation could be resumed.

My contribution to the art involves the simultaneous filling of all the sections of a single pad through the medium of multiple nozzles and cooperating telescoping sleeves, and includes mechanism for apportioning and distributing the filling material to the nozzles uniformly so that filling material of given density and volume under equal pressure will be delivered to each nozzle simultaneously.

My invention also includes mechanism whereby pads, the sections of which vary in width and thickness, may be filled in one operation.

To better understand the workings of my machine, reference should be had to the accompanying drawings in which:

Figure 1 is a top plan view of the assembled mechanism;

Fig. 2 is a side plan view of the assembly shown in Fig. 1;

Fig. 3 is a top plan view of the nozzle and fan assembly showing a multiple nozzle assembly introduced into a pad;

Fig. 4 is a side plan view of the assembly disclosed in Fig. 3 and illustrates the manner in which the nozzle sleeves are withdrawn from the pad and transferred to the top of the pad mold;

Fig. 5 is a front plan view of the mold track;

Fig. 6 is a front plan view of an assembled set of nozzle sleeves;

Fig. 7 is a top plan view of a mold with a set of nozzle sleeves partially withdrawn therefrom;

Fig. 8 is a longitudinal section view on the line 8—8 of the set of sleeves disclosed in Fig. 6; and

Fig. 9 is a fragmentary perspective of a modified nozzle unit associated with a mold.

Referring again to the drawings and more particularly to Figs. 1 and 2, the numeral 10 is generally used to indicate a filling material feeder of the usual type and construction which is used for primary break-down of the baled filling ma-

terial. That is to say, the member 10 is in the nature of a primary disintegrator to break down the formerly baled filling material.

The feeder or disintegrator 10 has a hopper 11 into which the filling material is deposited and upon actuation of the feeder mechanism, through the medium of a drive 12, the filler material is initially broken up and cleansed, the cleansing operation being performed by a vacuum fan 13 which draws dust and other foreign substances from the cotton in the breaking-up process out of the feeder to a dump.

The partially broken up filling material is then automatically deposited onto a travelling apron 14 which carries it into the hopper 15 of a standard willow 16. The willow 16, actuated by a drive pulley 17, further agitates and breaks up the filling material and from thence it is drawn into a standard cotton condenser 18 which, when actuated through the medium of drive 19, again acts on the filling material to break it into still finer particles and further cleans it. The material is drawn from the willow to the condenser by vacuum, the lowering of the atmospheric pressure within the willow and condenser being accomplished by a fan 20 driven by a pulley 21 which connects with the condenser housing.

The material comes out of the condenser on a travelling apron 22 and is discharged into a hopper 23 of a receiver in the nature of a standard volumetric control device such as is made by Proctor and Schwartz of Philadelphia for the cotton industry. This device, when actuated by the drive 24, further breaks up the filling material and delivers it to a travelling apron 25 in a sheet of thoroughly broken up and cleansed filling material, the density, thickness and width of which is uniform throughout. The uniform mass of filling material is conveyed to rotating cutters 26 mounted on a shaft 27 which, in the instance of the structure shown in the drawings, divide the material into three portions of uniform width, thickness and density. The cutters mounted on the shaft 27 contact a slowly rotating roller or shaft member 28 which assists in conveying the filling material through the cutting operation to aprons 29 of standard cotton picking machines 30.

As illustrated in Figure 1, each picker 30 is provided with a separate outlet 330 which leads to the associated blower 38 thereof. That is to say, each picker 30 is in feeding relation to the related blower thereof and has no communication with the other blowers so that the separate masses of material being separately handled by the several pickers are separately fed to the separate blowers 38 and are conveyed while thus separated through the members 40 to the sections of the pad being filled.

The cutters 26 are adjustable on the shaft 27 so that the mass of filling material conveyed thereto may be separated in variable widths and thus variable quantities. This is important as in the instance of pads having alternate wide and narrow sections sewn therein, it is necessary that more or less filling material be supplied to the alternate wide and narrow sleeves, it being obvious that where the same quantity of filling material be blasted into the small sleeve as into the wider sleeve that trouble would immediately result. The filling material would build up more quickly in the small sleeve than in the large sleeve and eventually clog the nozzle. Therefore, by mounting the cutters in a manner as to permit relative adjustment of them, a proper

amount of filling material for each section of a pad is assured.

The whole system is connected with a large vacuum fan and interconnecting pipes so that at points in the operation where waste filling material accumulates it may be carried back to the feeder hopper through the action of the fan. The preferred design as shown in the drawings includes return pipes 31 and 32. Waste outlets 33 and 34 are positioned adjacent the outer cutting knives 26 so that fringes of stuffing material cut by the outside knives may be carried off and returned to the feeder hopper to be used again.

As the three uniform masses of filling material pass through the cutting knives they are deposited on travelling aprons 29 of the pickers which convey them through rollers 35 to the picking mechanism. At this point it is well to note that the speed of the apron 25 of the volumetric control machine, the speed of the rotation of the cutting knives and that of the aprons 29 is such that the prepared and divided material is conveyed to the pickers at a uniform rate of speed. The picker mechanisms are actuated by a single shaft 37 driven by a pulley 36 and inasmuch as the mechanism of the various pickers is of uniform size and travel at uniform speed, the same quantity of filling material will be exhausted from each.

Connected to the exhaust orifices of the pickers are fans of the same size and capacity. Therefore, the intake and output of filling material into and from the said fans is uniform. The pressure outlet of each of the fans connect tubular nozzles 40, such as are disclosed in my co-pending application, Serial Number 669,112 filed May 3, 1933. Each of the said nozzles 40 are formed at the free ends of divergent conduits or nozzles 41 discharging at different levels and leading from a common supply conduit or pipe section 42 which, in turn, connects with the fans 38 which, as stated above, draws the decimated cotton from the various pickers and forces it through one or the other of the oppositely disposed nozzles under air pressure.

Inasmuch as the flow of the material is to be alternated from one nozzle of a pair of divergent nozzles to the other, a valve 43 is disposed at the jointure of the two nozzles which, when actuated by the filling operator, will close off one or the other of the opposed nozzles as to permit flow of the material through one only.

An emergency valve 44 is positioned in the main supply conduit 42 so that in the event of trouble at the nozzles, the flow of material can be diverted from the nozzles to an emergency exhaust 45 which connects into the general exhaust return system indicated in Fig. 1 by pipes 31 and 32 and the connected fan. Therefore, should for any reason it be desirable to deflect the flow of material from the nozzles, it is only necessary for the operator to close the valve 44, which operation opens the emergency exhaust port as to permit the material coming from the blower to be carried back to the feeder hopper.

The valves of the three multiple nozzles shown are interconnected so that operation of them is simultaneous. For example, when it is necessary to divert the flow of filling material from the upper to the lower nozzles, operation of the valve control means 43 will operate the deflector valves of the said nozzles simultaneously. Also if it is necessary to shut off the flow of the material to all of the nozzles, operation of the valve 45

control mechanism 44 will close all the shut-off valves and open the emergency exhaust ports simultaneously.

The mold carriage and molds which support the pads to be filled are similar to those described in my co-pending application, Serial Number 669,112 filed May 3, 1933, except that the sleeves positioned in the pad to be filled are so fixed together as to form a unit. This will be best understood by referring to Figs. 3, 4, 6, 7, and 8. Fig. 7 discloses a mold 46 in which a pad has been positioned and a sleeve unit 47 inserted in three orifices of the pad. The sleeves are beveled outwardly at one end and are fixed together by a clamp member 48 which facilitates the withdrawing of the sleeves from the pad during the filling process.

As in the instance of the structure shown in my above mentioned co-pending application, the molds are adapted to travel on parallel-spaced tracks 50 and 51 which are positioned adjacent the orifices of the diverging supply nozzles. The said tracks are so spaced as to permit alignment of pad molds with the exhaust orifices of the staggered parallel supply nozzles, one of the said nozzles being positioned to fill pads in molds riding on the lower track and the other to fill pads in molds riding on the adjacent track.

In order to facilitate the travelling of the molds along the track, wheels 52 are provided, the said wheels being fixed to the bottom of the molds. The mold per se has a solid bottom 53 and a perforated top 54 as to permit exodus of air within the pad when the pad is being filled. Means are provided to lock the mold in closed position when the pad is placed therein.

Referring again to the drawings, attention is called to Fig. 9 which discloses a unit of three sleeves, the two outer ones being of small diameter and the middle one of large diameter. The sleeves are shown inserted in a pad, here shown as having a plurality of sections or constituent pads the two outer sewn sections of which are of small diameter and the middle one of large diameter. In order to fill such a pad, the nozzles are unjointed at the hinges and ones of proper size are attached. By proper size I refer to the dimensions of the reduced portion of the nozzle, over which the sleeve units are adapted to telescope. For instance, to be used in conjunction with the pad disclosed in Fig. 3, the middle nozzle would be taken off and the one substituted would have its reduced end of a diameter and contour slightly smaller than the diameter and contour of the sleeve in the smaller pad section, which sleeve will be telescoped over it.

Inasmuch as the adjustable cutters 26 so function as to provide a given quantity of cotton to each picker, and thus to each nozzle, and the air pressure from the fans 38 is uniform, each section will receive a proper amount of filling material and the filling operation will be exactly the same as in the instance of pads having the same size sleeves.

At this point it should be noted that although a multiple of three interconnecting nozzles are shown, the apparatus may be changed as to have a larger or lesser number of nozzles so that in the event a pad having six sewn sections is to be filled, the apparatus can be assembled in multiples of six so that the six-section pad may be filled in one operation, and, as explained herefore, the apparatus is capable of simultaneous filling of a section pad, the sections of which are not uniform as to width.

The apparatus functions as follows:

A loading operator will insert the multiple sleeve unit in the three-section pad, load the said pad in the mold and roll the pad to a predetermined stop on the track, which stop serves to align the flared ends of the pipes with one set of the nozzles 41, the set depending on whether the mold is on the upper or lower track. The filling operator grasps the handle 49 of the sleeve unit and draws the sleeve out of the mold onto the filling nozzles 41. The flow of filling material is then diverted to that set of nozzles and as the filling material is blasted through the sleeve to the rear end of the pad, the operator slowly withdraws the sleeve unit from the pad onto the nozzles, the speed of withdrawal being determined by the speed with which the filling material fills up the pad ahead of the sleeve unit, it being desirable to keep the sleeve approximately an inch away from the packed material ahead of it. As the ends of the nozzle unit approach the outer ends of the various sections of the pad, the filling operator actuates the stem of the valve 43 and the filling material is diverted to the other nozzles where a pad has been positioned by a second filling operator. The said second filling operator then begins the filling of his pad and in the interim of the said filling, the first named operator pulls the sleeve unit as to cause the said unit to clear the top of the mold, slips the unit off the nozzle onto the top of the mold, whereupon the said filling operator pushes the loaded pad down the track to an unloading operator and draws another mold containing an empty pad into position adjacent the nozzles. It may be clearly seen that the filling operation is continuous as when the operator of the top set of nozzles completes the filling of his pad, he diverts the flow of material from his set of nozzles to the adjacent set of nozzles which the other filling operator has, in the meantime, connected with another pad to be filled. However, as the filling operation has been thoroughly described and explained in my heretofore mentioned co-pending application, it is not thought necessary to go into detail respecting it.

Having described my invention, what I claim and desire to secure by Letters Patent is:

1. Filling apparatus for a plurality of pad sections comprising the following instrumentalities, arranged serially, a primary disintegrator for preparing and cleaning raw filling material, a receiver for the material from the primary disintegrator and having means for forming it into a sheet of uniform density and thickness, means for severing said sheet longitudinally into strips, in number and width corresponding to the number and capacity of the pad sections to be filled, a secondary disintegrator, for comminuting said strips, maintaining them separately during treatment, and blower means receiving the separate masses of material from said secondary disintegrator and delivering the same separately to the said corresponding pad sections.

2. Filling apparatus for a plurality of pad sections comprising the following instrumentalities arranged serially, a primary disintegrator for preparing and cleaning raw filling material, a receiver for the material from the primary disintegrator and having means for forming it into a sheet of uniform density and thickness, cutting means adjustable widthwise of the sheet for severing it longitudinally into strips in number and width corresponding to the number and capacity of corresponding pad sections to be

- filled, a secondary disintegrator for comminuting said strips, maintaining them separately during treatment, and blower means receiving the separate masses of material from said secondary disintegrator and delivering the same separately to the corresponding pad sections.
3. Filling apparatus for a plurality of pad sections comprising the following instrumentalities arranged serially, a primary disintegrator for preparing and cleaning raw filling material, a receiver for the material from the primary disintegrator and having means for continuously forming it into a sheet of uniform density and thickness, cutting elements adjustable transversely of the sheet for continuously severing it longitudinally into strips in number and width corresponding to the number and capacity of corresponding pad sections to be filled, a secondary disintegrator for comminuting said strips, maintaining them separately during treatment, and blower means receiving the separate masses of material from said secondary disintegrator and delivering the same separately to the corresponding pad sections.
4. Filling apparatus for a plurality of pad sections comprising the following instrumentalities, arranged serially, a primary disintegrator for preparing and cleaning raw filling material, a receiver for the material from the primary disintegrator and having means for forming it into a sheet of uniform density and thickness, means for severing said sheet longitudinally into strips, in number and width corresponding to the number and capacity of the pad sections to be filled, a secondary disintegrator for comminuting said strips and maintaining them separately during treatment, blower means, a plurality of nozzles unitarily related and hingedly joined to said blower means, adapted to deliver the masses of material simultaneously to a plurality of filling tubes placed in said pad sections and telescopically related to said filling tubes in the longitudinal withdrawal of said filling tubes from said pad sections.
5. In a filling apparatus for pads having a plurality of sections, a receiver for filling material and having means for forming it into a sheet of approximately uniform density and thickness, means for severing the sheet into strips, in number and width corresponding to the number of pad sections to be filled, a disintegrator for comminuting said strips and maintaining them separate during treatment, and blower means receiving said separate masses of material from said disintegrator and delivering the same to the pad sections.
6. In a filling apparatus for pads having a plurality of sections, a disintegrator for material, a receiver for the material from the disintegrator and having means for forming it into a sheet, means to divide the sheet into strips, a second disintegrator for comminuting said strips and maintaining the same separate during treatment, and means receiving the separate masses of material from said second disintegrator and deliv-
- ering the same separately to the corresponding pad sections.
7. In a filling apparatus for pads having a plurality of sections, a disintegrator for the raw material, a receiver for the raw material from the disintegrator and having means for forming it into a sheet, means for dividing said sheet into strips, a second disintegrator for comminuting the previously formed strips, and blower means receiving the separate masses of material from said second disintegrator and delivering the same to the corresponding pad sections.
8. In an apparatus for filling the sections of pads, a disintegrator for the raw material, a receiver for the raw material from the disintegrator and having means for forming the material into a sheet of uniform density and thickness, means for dividing said sheet into strips, and blower means receiving the material in said strips and delivering the same separately to the pad sections to be filled.
9. In a filling apparatus for pads having a plurality of sections; a willow; a receiver for the material from the willow and having means for forming the material into parts of approximately uniform density; a picker for treating said newly formed parts of material and having means for maintaining the same separate during treatment; and a plurality of separate blowers receiving the said separated parts of material from the picker and having means for handling the same in preparation for introduction to the corresponding sections of the pad being filled.
10. In an apparatus for filling pads having a plurality of sections; a primary disintegrator for material; a receiver for the material from said disintegrator and having means for forming it into a sheet of approximately uniform thickness and density; cutters for dividing said sheet longitudinally into separate strips; a secondary disintegrator for treating the material in said strips and maintaining such material in separate parts during treatment; said secondary disintegrator being provided with separate outlets; separate blowers having communication with said outlets; and separate material conductors separately connected to said blowers for the movement of the separate masses of material to the sections of the pad to be filled.
11. Apparatus for simultaneously filling a plurality of pads arranged side by side, which pads are of substantially equal length but may be of different capacity, said apparatus comprising means for feeding a mass of suitable filling material in a stream, driven apportioning means for dividing said stream into separate parts which correspond in number and in relative volume to the number and relative capacities of the pads, conduits for directing said parts separately to the respective pads, and blower means for supplying air directly to the conduits to propel said parts along said conduits to said pads whereby to complete filling of the latter substantially simultaneously.
